MOP AND SHAKER ROD

Joseph P. Bem, San Jose, Calif.

Application June 26, 1948, Serial No. 35,449

3 Claims. (Cl. 15—147)

1

This invention relates to improvements in mops and brushes and shaker rods therefor, and more particularly relates to shaker rods for oscillating the head of a mop having flexible tufts or strands forming an aggregate mop head which is usually mounted at an end of an elongated handle.

Since the invention would be equally advantageous with a mop head or a bristle brush, the general term mop is used inclusive of both of said facilities.

Mops of the type having a head of flexible tufts or strands mounted at the end of a handle are well known for dusting or swabbing surfaces. These types of mops almost invariably have a pivot connection between the mop head and handle so that the handle may be adjusted at varying angles to the mop head for more convenient use of the mop at different positions of manipulation, for inserting the mop head into narrow spaces, such as under furniture, for change of mop head when worn out, for shaking the accumulations of dust or dirt from the mop strands and for other purposes.

The present invention has among its objects to provide means for oscillating a mop head on its pivotal connection with a handle member.

A further object is to provide a mop shaker rod device readily and easily attached to a mop assembly of head and handle.

Other objects are to provide resilience in a rod for shaking a mop head from a position on the mop handle; to provide stop means for abruptly delimiting the oscillations of a mop head when shaken by a shaker rod on the mop handle; to provide shaking means for a mop head which is economical to manufacture, rugged in construction and efficient in operation, and generally to improve upon devices of the character described.

With the foregoing and other objects in view, which will be apparent from or specifically pointed out in this specification, one form in which the invention may be exemplified is described herein and illustrated in the several views of the accompanying drawing, it being understood that variations of specific structure may be resorted to without departing from the invention which is defined in the appended claims.

In the accompanying drawing:

Fig. 1 is a perspective view of shaker rod of the invention.

Fig. 2 is a fragmentary side view of Fig. 1 partly in section.

Fig. 3 is a fragmentary perspective of a part of the structure of Fig. 1, partly broken away.

2

Fig. 4 is a fragmentary cross section on line 4—4 of Fig. 2.

Fig. 5 is a modified form of handgrip member.

Fig. 6 is a perspective view of modified form of frame member.

Fig. 7 is a side view partly in section of a portion of frame member of Fig. 6, showing positions of operation.

Referring to the drawing in which like reference characters indicate corresponding operational parts in the several views, and particularly referring to Figs. 1 and 2, an elongated conventional handle member 10 of a suitable length is provided at its connecting end with a ferrule socket 11 having an extended arm 12. The extended ferrule arm has an opening or eye 13 adjacent its free end, by which a mop head or brush, generally indicated 14, may be pivotally secured thereto.

The mop head may be made of any suitable type having a back member or other suitable means to which the ferrule arm of the handle may be pivotally connected. As illustrated herein, the back of the mop comprises an open frame 15 of the nature of a broken loop generally triangular in plan and having a break in continuity as to be open at one angle portion as at 16 for

sliding thereon a padded flexible tubular stringer 17 for the mop, the strands or tufts 18 of the mop being secured to the stringer in any suitable manner. The mop member is therefore readily removable and replaceable on the frame, either for laundering or mounting a new mop member.

Opposite the opening 16 the triangular frame may have bracket 19 extended inwardly and forwardly from its rear base bar toward its central portion and formed by retroverting the frame member upon itself providing a retroverted looped end 19b, as shown in Fig. 3. The bracket arms 20 and 21 which are connected at one end by the looped end 19b of the bracket are relatively spaced and parallel and have an eyelet at 22 therethrough for registering with the eyelet 13 of the extended arm of the handle ferrule, so that a pivot pin 23 may be inserted therethrough,

whereby the frame of the mop head and the handle are connected pivotally.

Within the triangular frame and the padded tubular stringer 17 which is slid thereon from the open angle, there may optionally be provided a pan or plate 24, which would correspond with the back of a bristle brush. This pan or plate 24 may be fixed in place by an integral central upformed flange on each side of the central bracket 19 of the frame and secured thereto by

the pivot pin 23. The pan or plate 24, when employed with an oil or liquid mop, may have holes 26 therein so that oil or other liquid may be placed in the pan, and be absorbed into the mop body. As is sometimes customary, wire loops 25 may be passed through the holes 26 and around the stringer 17 and intertwined at the ends to further support the pan. As described thus far, the mop of Figs. 1 and 2 are well known.

One feature of this invention is to provide an improved means whereby the mop head may be oscillated upon the pivotal mounting with the handle for shaking from the mop strands, or from bristles in a brush, the accumulation of dust, dirt, fibers and other matter collected on the mop or brush by its use. Such a means, as exemplified in Figs. 1 and 2 is especially adapted as an auxiliary attachment for mops or brushes previously constructed without such facility, whereas in Figs. 6 and 7 as will be further described, a specially designed frame is provided.

Again referring to Figs. 1 and 2, there is provided a shaker rod member 27 which preferably is relatively thick spring steel wire, approximately three-sixteenths inch diameter being satisfactory, so that when reciprocated axially it may, for all practical purposes of shaking a mop, be considered as rigid. At one end the rod is formed to a plurality of integral helical coils 28 which are a continuation of rod 27 and when slid upon the handle 10 provide a handgrip member. The handgrip member is of a diameter slightly greater than the diameter of the handle 10 so as to have a freely slideable fit thereon. The coils of the handgrip portion are relatively spaced and substantially stiff as single coils, though the coil form provides just sufficient resilience in the plurality of coils to eliminate an abrupt jar when the rod reaches the opposite limits of amplitude in its reciprocation. However, the coils are not sufficiently resilient to come into relative contact and pinch the flesh of the operator's hand when reciprocating the rod.

The opposite end of the rod is provided with an eyelet 29 loosely engaged around a pivot pin 30 which is mounted between opposed spaced arms of a clevised link member 31. The base of the clevised link member is provided with a base pin 32 for insertion through an orifice 33 in the back plate or pan 24 of the mop and suitably secured tightly relative to the back of the mop, as by a cap nut 34.

Thus the rod and handgrip member of Figs. 1 and 2 may be installed on previously constructed mops merely by drilling the hole 33 in the back member or pan plate 24, and then mounting the shaker rod by first slipping the coiled handgrip over the opposite free end of the mop handle and attaching to the back of the mop head the base pin of the clevised link member and its pivotal connection at the opposite end of the rod. Obviously, the clevised link member may be first mounted separately to the back of the mop and the pivot pin 30 inserted through the eye of the clevis and eye of the rod.

From the foregoing description it will be apparent that upon reciprocating the handgrip 28 the mop will be pivotally moved on the pivot pin 23 which passes through the frame eyelet 22 and opening 13 of the extended ferrule arm 12, thus tilting or oscillating the mop head on the handle pivot from normal position to the position shown in dash lines of Fig. 2. Upon reciprocation of the shaker rod 27 in one direction towards the

free end of the handle, the looped end 19b of the retroverted bracket arms 20 and 21 will be swung in the arc of the handle pivot 23, and abruptly stop with a jolt by striking against the edge of the extended arm 12 of the ferrule member; and upon reciprocation of rod 27 in the opposite direction towards the mop head, the portion of the mop stringer and frame 15 at the inturned end or base of bracket 19 will stop with a jolt against the ferrule portion of the handle, as in Fig. 2. The rapidity of reciprocation of the hand grip and rod determines the degree to which the mop is thus shaken and abruptly stopped with a jolt at the end of each stroke of reciprocation of the shaker rod to rid it of accumulated dirt and dust.

In Fig. 5 a modification of handgrip member is disclosed. The rod 27 and its coiled portion 28 may be substantially the same as in Figs. 1 and 2, except that at the terminal end of the coil 20 there is provided as a handgrip, a slide sleeve 35 which has one end connected to the coiled portion, as by a tightly engaging loop 36 of the terminal coil around one end of the sleeve member. In employing this form of handgrip, the number 25 of individual coils may, if desired, be reduced in number, yet providing a resilient means to eliminate jar in the shaking of the rod.

In Figs. 6 and 7 there is provided a modified hand especially adapted form of frame 15a. In shaking a mop, the efficiency in removing accumulated dirt is greatly enhanced if at the end of the oscillation movement in each direction the movement of the mop head is stopped abruptly with a jar. The frame of the modification shown in Fig. 6 provides such a means. The supporting frame of the mop, as in Figs. 1 and 2, may be a generally triangular loop which has a break or opening 16a at the apex angle for inserting a mop thereon. In this modification the frame 15a preferably is made of two pieces, each bent upon itself forming one-half of the triangle in plan, each of the pieces having an extended bracket arm as indicated 20a and 21a, which, in the completed triangular frame, extend inwardly and forwardly from the rear base bar toward the central portion of the triangular frame, the bracket arms being relatively spaced and parallel. But instead of being joined by a retroverted connection at the inner ends of the arms as in Fig. 1, the arms 20a and 21a are angularly or arcuately formed upwardly so that the free ends thereof are spaced from the general plane of the triangle frame, as at 19a.

At approximately midway intermediate the ends of the bracket arms 20a and 21a they are perforated for the eyelet 22 to receive the pin 23 upon which the end of the arm 12 of handle ferrule 11 is pivotally mounted. By making the frame member in two pieces, they may be more conveniently perforated with necessary holes while in the flat, and thereafter formed as desired.

The bracket arms 20a, 21a are relatively spaced by a pair of stop members 37, 38. These stop members are, respectively, spaced forwardly and rearwardly of the pivot connection of the handle member to the frame, the forwardly stop member 37 being intermediate the connecting pivots for the handle and shaker rod, respectively, the said pivotal connections and the stop members being in alignment between the parallel bracket arms. The stop members may be securely and fixedly swaged to the arms of the frame and thus not only space the arms, but also serve to sup-

port and securely connect the two portions of the frame.

The upformed end 19a of the arms of the bracket of the frame has an eyelet therethrough to receive pivot pin 30, the latter being engaged by the loop eyelet 29 at one end of the shaker rod 27. The hand grip of the rod in Fig. 6 may be of either type heretofore described.

Upon reciprocation of the hand grip member and shaker rod of Fig. 6 the mop head is oscillated on the handle pivot 22. As shown in Fig. 7, upon the upward oscillation of the mop head the stop member 37 strikes upon the upper surface of ferrule arm 12, and upon the downward oscillation of the mop head the stop member 38 strikes upon the lower surface of the ferrule arm, bringing the mop head at the end of each oscillation to a stop with a jolt which forcefully shakes the mop strands and loosens and discharges accumulated dust and dirt in the mop body. Obviously, as previously described, the rapidity of the reciprocation of the hand grip and rod will determine the force of the jolting stop of oscillations of the mop and the efficiency of the shaking cleaning operation.

Having described the invention, what I claim as new and patentable is:

1. A shakable mop device comprising a mop head including a mop supporting frame, an elongated handle pivotally connected to said frame centrally of the plane of the frame, means for oscillating the said frame on the pivotal connection of the handle, including a shaker rod having at one end a pivotal connection to said mop supporting frame in spaced relation to said pivotal connection of the handle and which, when reciprocated, is adapted for oscillating the mop head on the handle pivot, said shaker rod having at its opposite end portion an integral helically coiled portion slidably mounted circumferentially of the handle and adapted for gripping by the operator as a hand grip for reciprocating the shaker rod, said mop head having stop members disposed in spaced relation on opposite sides of and in alignment with the pivotal connection of the handle and adapted for contacting the handle adjacent the pivotal connection of the mop head when the mop head is oscillated by the shaker rod, and one of said stop members being intermediately spaced between the respective pivotal connections of the shaker rod and handle.

2. A mop device comprising a supporting frame generally triangular in plan and having a rearward base bar and an apex angle, said apex angle having an opening whereby a mop body may be removably mounted on the frame, an elongated handle pivotally connected to said frame centrally of the plane of the frame, means for oscillating the frame on the handle pivot including a shaker rod having at one end a pivotal connection to the frame at a central portion of the plane

of the frame and in spaced relation to the pivotal mounting of the handle, a hand grip member at the opposite end of the rod slidably mounted circumferentially of the mop handle, and stop members carried by the frame in spaced relation on opposite sides of and in alignment with the pivotal connection of the handle and adapted to strike the handle adjacent the pivotal connection of the mop head when the mop frame is oscillated and thereby delimit such oscillation, one of said stop members being intermediately spaced between the respective pivotal connections of the shaker rod and the handle.

3. A mop device for mounting a mop body, including a frame support for said mop body, said frame being substantially triangular in plan, an elongated mop handle having one end pivotally connected to a central portion of the plane of said frame support, a shaker rod having at one end a pivotal connection to a central portion of said frame support and in spaced relation to the pivotal mounting of the handle, a hand grip member connected to the opposite end of the rod and slideable on the handle, said rod and hand grip being reciprocable whereby the mop head may be oscillated on the pivot mounting of the handle, said frame support having relatively spaced parallel bracket arms extended inwardly towards the central portion of its plane, the said respective pivotal mountings of the handle and shaker rod being between said parallel bracket arms, and stop members between said arms and relatively spaced on each side of said handle pivot, one of said stop members being mounted between the respective pivotal mountings of the handle and shaker rod, said stop members being adapted for striking against the handle member adjacent the pivotal mounting of the mop head when the mop head is oscillated by the shaker rod.
